United States Patent Office.

LEWIS WILSON, OF OVID, NEW YORK, ASSIGNOR TO HIMSELF AND ANDREW DUNLAP, OF SAME PLACE.

Letters Patent No. 71,352, dated November 26, 1867.

IMPROVED BED-BOTTOM.

The Schedule referred to in these Letters Patent and making part of the same.

TO ALL WHOM IT MAY CONCERN:

Be it known that I, LEWIS WILSON, of Ovid, in the county of Seneca, and State of New York, have invented a new and improved Spring-Bed Bottom; and I do hereby declare that the following is a full, clear, and exact description thereof, reference being had to the accompanying drawings, making a part of this specification, in which—

Figure 1 is a plan view of the improved bed-bottom.

Figure 2 is a longitudinal section taken in a vertical plane through the same.

Figure 3 is an elevation of one end of the bed-bottom.

Figure 4 is an enlarged sectional view in detail, showing the manner of attaching and supporting the ends of the slats.

Similar letters of reference indicate corresponding parts in the several figures.

The nature of my invention consists in suspending the slats constituting the bed-bottom from rollers or rolling bars by means of strips of cloth, which are wound upon these rollers, and in combining springs therewith in such manner as to afford elastic supports for the slats, and to keep them all in a horizontal plane, and, at the same time, allow them to rise and descend together, as will be hereinafter described.

To enable others skilled in the art to understand my invention, I will describe its construction and operation.

In the accompanying drawings, A represents a four-post frame, composed of four posts secured together by longitudinal and transverse bars, as shown in the drawings. This forms a frame which is adapted for receiving and supporting the several parts composing the spring-bed bottom, and which can be applied to or removed from a bedstead at pleasure. B B represent two horizontal transverse rollers or rolling bars, having their end bearings in the four posts of the frame A. These rollers have strips *a a*, of canvas, nailed upon them, and extending from end to end, as shown in fig. 1, which strips are wound upon their respective rollers, and provided with hooks *b b*, by means of which strips *c c* of canvas can be attached to or detached from the said strips *a a*, as shown. The strips *c c* are secured fast to the ends of the slats D D by slitting these slats, inserting the edges of the strips of canvas into the slits, and then securing the parts together by small nails, as shown. Near the extremities of each roller B annular grooves are formed, so as to reduce the diameter of the rollers, and adapt them for receiving bands or straps *d d*, and allow the latter to roll up and unroll without interfering with the canvas strips *a a*. The straps are secured upon the rollers so as to wind upon and unwind in opposite directions to the strips *a a*; and these straps are also secured to the ends of flat springs *g g*, which are fastened to cross-bars of frame A beneath the rollers B.

It will be seen, from the above description, that the slats D are suspended from two rollers B B by means of flexible but inelastic strips, and that these slats are sustained by means of the springs *g g*, acting through the medium of the straps *d d*, rollers B, and said flexible strips. This arrangement will keep the slats horizontal, and prevent them from tilting laterally; and, while this is the case, the slatted bottom is allowed to move freely in an endwise direction, and to rise and descend more or less, according to the weight which is upon it.

I would here state that, while my invention is designed for bed-bottoms, it is also equally applicable for the purpose of a seat for vehicles. I do not, therefore, limit myself to its application for the purpose of a bed-bottom; but also intend its use for the purpose of a seat wherever a seat may be required.

Having described my invention, what I claim as new, and desire to secure by Letters Patent, is—

1. A spring-bed bottom, the slats of which are suspended from rollers B B by means of strips of cloth, in combination with springs *g g* and the connecting-straps *d d*, arranged substantially as described.
2. Securing the slats composing the bed-bottom to strips of cloth *c c*, attached, by hooks or their equivalents, to strips *a a*, which are wound upon rollers, substantially as described.

LEWIS WILSON.
